(57) **CLAIM**

The ornamental design for an electric vehicle, as shown and described.

DESCRIPTION

FIG. 1 is a front perspective view of an electric vehicle showing the new design in a first embodiment.

FIG. 2 is a front view of the electric vehicle of FIG. 1.

FIG. 3 is a rear view of the electric vehicle of FIG. 1.

FIG. 4 is a first side view of the electric vehicle of FIG. 1.

FIG. 5 is a second side view of the electric vehicle of FIG. 1.

FIG. 6 is a top view of the electric vehicle of FIG. 1.

FIG. 7 is a bottom view of the electric vehicle of FIG. 1.

FIG. 8 is a front perspective view of an electric vehicle showing the new design in a second embodiment.

FIG. 9 is a front view of the electric vehicle of FIG. 8.

FIG. 10 is a rear view of the electric vehicle of FIG. 8.

FIG. 11 is a first side view of the electric vehicle of FIG. 8.

FIG. 12 is a second side view of the electric vehicle of FIG. 8.

FIG. 13 is a top view of the electric vehicle of FIG. 8; and,

FIG. 14 is a bottom view of the electric vehicle of FIG. 8. The dashed lines in the drawings represent environmental structure that forms no part of the claimed design.

1 Claim, 14 Drawing Sheets
